(57) **CLAIM**

The ornamental design for a motor housing, as shown and described.

DESCRIPTION

FIG. 1 is a perspective view showing my new design for a motor housing;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof showing the device in another side.

The broken lines in FIG. 3 show portions of a motor housing that form no part of the claimed design.
